THEFT-PREVENTION APPARATUS

Application filed January 21, 1929. Serial No. 333,872.

This invention relates to an apparatus that is intended to be used primarily for preventing a robber, such as a hold-up man, from gaining access to a device or compartment in 5 which money or other valuables are kept, or from forcing any person to remove the valuables from said device or compartment and deliver up said valuables.

It is common practice in many business 10 establishments, such as grocery stores, gasoline filling stations, etc., to keep considerable sums of money in cash registers, money drawers and safes which invariably are located at such a point in the establishment that a robber, 15 such as a hold-up man, can quickly remove the money or valuables from same while he holds the employees, occupants or customers of the establishment under subjection with a revolver, gun or other weapon. Accordingly, 20 establishments of the kind in which money and other valuables are kept in a cash register, safe or money drawer, are a prolific source of revenue to hold-up men, due to the ease with 25 which a robber having little or no skill can enter such an establishment, intimidate the occupants with a drawn weapon and then have access to the cash register or money drawer in which the valuables are kept. Even in an establishment in which the valuables 30 are kept in a safe provided with a combination lock, it is a relatively simple matter for a robber to force the owner or an employee to open the safe, due to the fear that is created in the mind of the average man when he is 35 confronted with the alternative of being shot or obeying the commands of a hold-up man.

The main object of my invention is to provide an apparatus that will effectively frustrate hold-ups in business establishments, 40 namely, robberies of the kind that are effected or carried out by a robber who enters a store or similar establishment while business is being transacted in same, then intimidates all of the occupants of the establishment with a 45 drawn gun and then quickly removes the contents of the cash register, money drawer or safe and departs almost before the occupants realize what has happened.

To this end I have devised an apparatus 50 that consists of a passageway proportioned

so that it is not large enough to hold more than one person at a time, and arranged so that it serves as the sole entrance to a compartment or space in which valuables are kept, an entrance door and an exit door for said 55 passageway so constructed and combined that the exit door leading from said passageway to the valuables cannot be fully opened to gain access to the valuables, unless the entrance door of said passageway has been 60 moved into its fully closed position, a latch for said exit door combined with same in such a manner that when said door starts to move towards its open position, said latch operates automatically and locks said door, thereby 65 preventing said door from being moved either into its open position or restored to its closed position, and a combination lock or similar means associated with said latch for preventing said latch from being manipulated or 70 tripped to release the exit door.

With an apparatus of the construction above described the only way that a robber can gain access to the compartment or place where the valuables are kept is by entering a 75 passageway and closing the entrance door of said passageway, for, as previously stated, the exit door leading to the valuables cannot be moved into its fully open position unless the entrance door to said passageway has previously been closed. There is little liability 80 of a robber taking such a chance, for he knows that if he enters the passageway and closes the entrance door of same, he will be cut off from the occupants of the establishment, and will thus be unable to intimidate 85 them, with the result that someone will surely escape from the establishment and give an alarm. If, however, a robber should have the temerity to enter the passageway of the 90 apparatus, close the entrance door of same and then endeavor to open the exit door leading to the valuables, he would be locked in the passageway by the action of the latch for the exit door that becomes operative automatically while the exit door is being moved towards its open position, said latch being controlled and retained in its locked or operative 95 position by a combination lock or similar mechanism that can only be operated by a person 100

son familiar with the construction and operation of same, and which is located in such a position that it is not visible to a person standing in the passageway. It is impossible for the robber to force an employee of the establishment to accompany him into the passageway, due to the fact that said passageway is not large enough to hold two persons. If the robber should compel an employee of the establishment to enter the passageway alone, this will avail him nothing, as it is impossible for the employee to gain access to the compartment or space in which the valuables are kept without first closing the entrance door to the passageway preparatory to opening the exit door. In doing this the employee would become protected from the robber, for the employee would be located in a closed passageway constructed preferably from sheet steel or some other bullet-proof material.

From the foregoing it will be seen that an apparatus of the construction described practically frustrates hold-ups or daylight robberies, such as are now being perpetrated extensively in business establishments, due to the fact that it comprises a bullet-proof passageway leading to a place where valuables are stored, proportioned so that two persons cannot enter and pass through the same at the same time and equipped with a plurality of doors and a door locking mechanism designed so that the door leading to the valuables can be opened only by a person familiar with the construction and principle of operation of the apparatus, and furthermore, can only be opened after the entrance door to the passageway has been fully closed.

An apparatus embodying my invention can be constructed either in the form of a sheet metal cabinet provided with two compartments, one of which serves as a storage space in which money or valuables can be kept, and the other serving as a passageway that leads to said space, or the apparatus can be constructed in the form of an attachment or adjunct for vaults, that may consist simply of a sheet metal housing adapted to serve as a passageway and equipped with an entrance door and an exit door that leads to a compartment of the vault in which valuables are stored.

Figure 1 of the drawings is a horizontal sectional view, illustrating an apparatus embodying my invention, combined with a vault so as to prevent a hold-up man from gaining access to the compartment of the vault in which valuables are stored.

Figure 2 is a horizontal sectional view, illustrating another form of my invention, consisting of a cabinet constructed from sheet metal and provided with two compartments, one of which serves as a storage space for valuables and the other serving as a passageway to said storage space.

Figure 3 is a vertical sectional view, taken

on the line 3—3 of Figure 2, looking in the direction indicated by the arrows.

Figure 4 is a horizontal sectional view, similar to Figure 2, taken on the line 4—4 of Figure 5, showing the entrance door to the passageway in its fully closed position, and the exit door from said passageway in its partially open position.

Figure 5 is a vertical sectional view, taken on the line 5—5 of Figure 4.

Figure 6 is an enlarged vertical sectional view of the latch for the exit door, taken on the line 6—6 of Figure 4.

Figure 7 is an enlarged side elevational view, partly in section, illustrating the latch for the exit door; and

Figure 8 is a horizontal sectional view, taken on the line 8—8 of Figure 6.

In the accompanying drawings, A designates a passageway, constructed preferably from sheet steel or some other suitable bullet-proof material, and proportioned so that it is only approximately large enough to receive one person standing in a normal upright position. The passageway A is so arranged that it constitutes the sole entrance to a compartment or space in which valuables are adapted to be stored. In the form of my invention shown in Figure 1 said storage space consists of a compartment B' in a vault whose interior is divided by a vertically-disposed partition 1, the sheet metal housing or casing 2 that constitutes the passageway A being permanently combined with and forming an integral portion of a swinging door 3 in the partition 1 that normally occupies a closed position, shown in full lines in Figure 1, said door 3 being held in its closed position by a retaining device 4 arranged on the inside of the partition 1, i. e., on the side presented towards the storage compartment B'. 85 90 95 100 105

In the form of my invention shown in Figure 2 which represents the preferred form of my invention, the passageway A is formed by one portion of a cabinet 2^a constructed from sheet metal or some other suitable bullet-proof material and made large enough so that a portion of the interior of said cabinet can be used to form a storage compartment B, as shown in Figure 2. Usually, the cabinet 2^a will be proportioned so that one-half of same will constitute a passageway A in which a person can stand in an upright position, and the other half will constitute a storage space or compartment for money and other valuables. 110 115 120 125

The passageway A in both forms of my invention is provided with an entrance door C of the sliding type, and an exit door D also of the sliding type. The entrance door C is used as a closure for the opening in one of the walls of the cabinet or casing through which a person can enter the passageway A, and the exit door D is arranged at right angles to the entrance door and is used as a clo- 130

sure for an opening leading from the passageway A to the storage space or compartment B or B'. The casing or cabinet of the apparatus is provided with a pocket C' that receives the entrance door C when said entrance door is moved into its open position, and said casing or cabinet is also provided with a pocket D' that receives the exit door D when said exit door is moved into its open position.

5 The details of construction of the cabinet and the doors C and D associated with same are immaterial and can be varied in numerous ways without departing from the spirit of my invention.

10 As previously stated, the entrance door C and exit door D of the passageway A are so constructed and arranged with relation to each other, that the entrance door must be in its fully closed position before the exit door can be opened, and the entrance door must be in its fully closed position before the exit door can be opened. In the form of my invention herein illustrated this result is attained by arranging the doors C and D at right angles 20 to each other, and disposing them in such relation that when the door C is moved into its pocket C', as shown in Figure 2, it serves as a stop or abutment against which the rear edge of the door D strikes, if an attempt is made to move said door D into its open position. Likewise, when the exit door D is moved into its pocket D', as shown in Figure 4, it serves as a stop or abutment against which the rear edge of the door C strikes, if an attempt is made to move said door C into its open position. The only way that the valuables in the storage compartment of the apparatus may be reached is by a person moving the entrance door C into its open position, then entering the passageway A, then restoring said entrance door C to its fully closed position, and thereafter moving the exit door D into its open position, whereupon the person may pass from the 25 passageway A into the storage compartment. In order to prevent the entrance to the storage compartment of a robber or other person not familiar with the construction and principle of operation of the apparatus, I provide the exit door D of the apparatus with a latch E, preferably of the spring-operated type, which is mounted on said door D in such a way that said latch will be inoperative when the door D is in its fully closed position, but said latch will operate automatically to lock the door D after said door has been moved slightly towards its open position, said latch E being controlled by or combined with a combination lock or similar mechanism 30 F that is used to retain said latch E in its operative position and prevent said latch from being tripped or rendered inoperative by a person not familiar with the combination of the lock F, or familiar with the method of operating the same. In other words, the apparatus is so constructed that the exit door D will become locked automatically in a partly open condition, during the operation of moving said door towards its open position, and further movement of said exit door D either to its wide open position or back to its closed position is prevented unless the person endeavoring to gain access to the storage compartment knows how to manipulate or actuate the combination lock F 70 that controls the latch E, on said exit door. The particular type or design of the latch E or other means that is used to arrest the movement of the exit door D towards its open position is immaterial, so far as my invention is concerned, and various types or kinds of combination locks or similar mechanisms may be used to prevent an unauthorized person from tripping or rendering inoperative the latch or equivalent device E that is associated with the exit door D, leading from the passageway A. In the form of my invention herein illustrated the latch E consists of a vertically-disposed plunger reciprocatingly mounted in a bearing 5 attached to the 80 side face of the door D adjacent the upper edge of same and combined with an expansion spring 6 that exerts pressure on said plunger in a direction to hold the upper end of said plunger pressed against a stationary bracket 7 arranged at one side of the path of travel of the door D, said bracket 7 having an elongated slot 7^a formed therein, as indicated in Figure 5, and also as shown clearly in Figure 7. When the door D is in 90 its fully closed position, the upper end of the plunger E bears against a solid portion of the bracket 7, thus holding the springs 6 under compression. As soon as the door D starts to move towards its open position, the plunger E comes into registration with the slot 7^a in the bracket 7 and moves upwardly into said slot, due to the force or pressure of the spring 6, thereby arresting the movement of the door D and preventing it from 100 being moved into its wide open position. The slot 7^a in the bracket 7 is preferably proportioned so that after the door D has been opened slightly, the plunger E will enter the slot in the bracket 7 and travel through said 105 slot while the door D is moving a trifle farther towards its open position, it being preferable to construct the apparatus in this way so as to permit the person who is endeavoring to gain access to the storage compartment to 110 insert his arm around the edge of the door and grasp an actuating device 8 on the plunger and manipulate the same in such a way as to trip the plunger or disengage it from the stationary bracket 7 with which it co-operates. 115 Usually, the actuating device 8 will consist of a chain or cord that depends from the lower end of the plunger E, and which is so arranged that it can be grasped easily by a person who passes his arm around the front 120 125 130

edge of the door D, after said door has been partly opened, as shown in Figure 5. Obviously, when the plunger E is moved downwardly or disengaged from the slot 7^a in the bracket 7, the exit door D can be moved into its wide open position.

It is impossible, however, for an unauthorized person, or person not familiar with the construction and principle of operation of the apparatus to pull the plunger E downwardly, so as to render it inoperative, and thus release the door D. Such movement of the plunger E is prevented by the part of the apparatus which I have referred to as the combination lock F for the latch of the exit door. Said combination lock is herein illustrated as being formed by two horizontally-disposed, screw-threaded shafts mounted in the bearing 5 in which the plunger E reciprocates, and provided with cut-out portions, designated by the reference character 9 in Figure 8, which are so disposed that they will register with the passageway 9^a in the bearing 5 in which the lower end portion of the plunger E slides, if the said screw-threaded shafts have been properly set or adjusted. In all other positions of said shafts portions of same project into the passageway 9^a, and thus act as a stop or abutment for the plunger E which prevents said plunger from being moved downwardly far enough to disengage said plunger or withdraw the upper end of same from the elongated slot 7^a in the bracket 7. Usually, each of the threaded shafts F will be provided at its front end with a non-circular-shaped portion 10, as shown in Figure 8, over which a removable operating handle 10^a, shown in Figure 5, can be slipped, so as to adjust or set the combination lock that is associated with the latch E.

In order to facilitate the use of the apparatus by an authorized person or persons, a means is provided for holding the latch E in an inactive or inoperative position, after said latch has been disengaged from the part 7 with which it cooperates to hold the exit door D against movement. One means that I have found to be efficient and highly practicable for this purpose consists of a spring-pressed bolt 11 arranged horizontally in the bearing 5 in such a way that when the plunger E is drawn downwardly far enough to withdraw the upper end of same from the slot in the bracket 7, said bolt 11 will snap into engagement with an annular recess or groove 12 in the plunger E, under the influence of the spring 13 that acts on said bolt, and which is shown in broken lines in Figure 7. In order that said holding device 11 will be tripped or rendered inoperative automatically after it has performed its function, and thus cause the latch E to be restored to such a condition that it will be ready to perform its function when the exit door D is thereafter moved towards its open position, I have provided the

bolt 11 with an extension 11^a, shown in Figure 7, that is adapted to strike against a member of the structure arranged in close proximity to the front edge portion of the door D when said door is restored to its fully closed position, preparatory to opening the entrance door C of the passageway A.

While the latch E and the combination lock F or other means associated with same can be constructed in various ways without departing from the spirit of my invention, I prefer to construct the apparatus in such a way that it is necessary for the user to set the combination lock or equivalent means in one position, i. e., to permit the latch E to be drawn downwardly, before the exit door D can be moved into its wide open position, and it is also necessary to adjust or set said combination lock or equivalent means in a different position before the exit door can be restored to its fully closed position. The main purpose, of course, in constructing the apparatus in this way is to eliminate the possibility of the user leaving the passageway A when the combination lock is in such a condition that it will not perform the function for which it is employed, i. e., to prevent an unauthorized person from rendering the latch E inoperative preparatory to moving the exit door into its wide open position.

In the form of my invention herein illustrated the latch E is composed of two elements, as shown in Figure 6, i. e., a top element that comprises the upper end portion of the plunger E in which the annular groove 12 is formed, and a bottom portion 14 to which the actuating device 8 is attached, said bottom portion 14 being capable of moving relatively to the upper portion of the plunger and being provided with a rod 15 that projects upwardly through a hole in the top portion of the plunger. At the upper end of said rod 15 is a head 16 which is positioned in a bore in the upper portion of the plunger E. A spring 6^a is combined with the lower portion 14 of the plunger E in such a way that it exerts upward pressure on the portion 14 of the plunger, and the component parts of the latch E of the structure are so proportioned and arranged that when the upper end portion of the latch is positioned in the slot 7^a in the bracket 7, the head 16 at the upper end of the rod 15 will be in engagement with the bottom or lower end of the bore in the upper portion of the plunger in which said head is positioned. Consequently, if the combination lock F has been set in such a position as to permit the latch E to be rendered inoperative, a downward pull on the actuating device 8 will cause the rod 15 to move the upper end portion of the plunger E downwardly out of engagement with the slot in the bracket 7. As soon as the upper end portion of the plunger E moves downwardly into its inoperative position, the spring 13

pressed bolt 11 snaps into engagement with the annular groove 12, and thus holds the latch E in an inoperative position until the exit door is thereafter restored to its fully closed position. As soon as the user releases the actuating device 8, however, the lower portion 14 of the plunger will move upwardly under the influence of its actuating spring 6^a, and thus cause the bottom end of said portion 14 to be positioned above the two horizontally-disposed threaded shafts F that constitute the combination lock or equivalent means that prevents an unauthorized person from tripping or releasing the latch E.

It will thus be seen that even when the upper end portion of the latch E is held in an inoperative position by the spring-pressed bolt 11, the shafts F can be turned into such a position that they act as a stop for the lower end portion 14 of the plunger which prevents said lower end portion from being drawn downwardly. In order to require the user to adjust said shafts F into this position, i. e., into a position to change the combination, or 25 in other words, prevent an unauthorized person from thereafter rendering the latch inoperative, the shafts F are mounted in the bearing 5 in such a way that they will strike against a stationary part of the cabinet located adjacent the front edge of the exit door when said door is moved back to its closed position, unless said shafts F have been turned into such a position that the cut-out portions 9 of same do not register with the 30 passageway 9^a in the bearing 5 in which the lower end portion 14 of the plunger moves. In using the apparatus it is absolutely necessary for the user to screw the shafts F rearwardly into the bearing 5 far enough to prevent the front ends of said shafts from striking against the stationary part of the cabinet when the exit door is restored to its fully closed position, and in doing this, i. e., screwing the shafts into such a position, the user 40 changes the combination and makes it necessary for the next user of the apparatus to adjust or manipulate the lock F properly before the latch E can be pulled downwardly so as to release the exit door and permit it to be 45 moved into its wide open position.

The method of using and operating the apparatus is as follows:

The money or other valuables which it is desired to protect are kept in the storage space B or B' of the apparatus, and the exit door D leading to said storage space from the passageway A is normally maintained in its fully closed position, as shown in Figure 2. If an authorized person desires to gain access 55 to the storage, he moves the entrance door C into its open position, then enters the passageway A, then restores the entrance door to its fully closed position, as shown in Figure 4, and then moves the exit door D towards its 60 open position. In the operation of open-

ing the exit door the latch E springs upwardly into the slot 7^a of the bracket 7, and thus arrests further movement of said door towards its open position, but said door has moved far enough to permit the user to pass his arm around the front edge of same and grasp the actuating device 8 and pull it downwardly, so as to trip the latch E, and thus release the door D, providing the combination lock F is set or adjusted so as to not interfere with the downward movement of the latch E. In order to properly set or adjust the combination lock F, the user manipulates the handle 10^a in such a way as to move the shafts F into such a position that the cut-out portions 9 of same will register with the passageway 9^a in the bearing 5 in which the plunger constituting the latch E reciprocates, after which the plunger E can be pulled downwardly and the door D can be 70 moved into its fully open position. To leave the passageway A it is necessary for the user to move the door D back to its fully closed position, preparatory to opening the entrance door C, and in this operation of restoring the exit door D to its fully closed position, the spring-pressed bolt 11 that constitutes the holding device for the plunger E is moved in a direction to release the plunger and permit it to move upwardly into engagement with a 75 solid portion of the bracket 7, and thus be in readiness to enter the slot 7^a in said bracket the next time the exit door D is moved towards its open position.

An apparatus of the construction above described is highly practicable for use in business establishments for storing money and other valuables, because it is of such construction that the employee or employees of the establishment who have custody of the valuables have easy access to the compartment or place where the valuables are kept. However, the apparatus effectively prevents an unauthorized person, such as a robber, from gaining access to the place where the valuables of the establishment are stored, due to the fact that entrance to the storage compartment can be effected only by manipulating or actuating a combination lock or equivalent mechanism associated with the exit door leading to the storage compartment from a passageway that constitutes the sole entrance to the storage compartment. Such an apparatus effectively prevents daylight robberies or hold-ups of business establishments, on account of the fact that the valuables are kept in an inaccessible place or compartment which must be entered through a passageway equipped with a plurality of doors, one of which must be fully closed before the door leading to the storage compartment can be fully opened, said passageway being of such size that it is impossible for a robber and an employee of the establishment to occupy the 80 passageway at the same time.

Having thus described my invention, what I claim as new and desire to secure by Letters Patent of the United States is:

1. An apparatus for the purpose described, comprising a cabinet provided with an entrance door through which access may be had to a passageway in said cabinet, an exit door leading from said passageway to a compartment in said cabinet which is used for storing valuables, said doors being of the sliding type and arranged in such relation that either of said doors when in a partly open position, blocks the other door or prevents the same from being opened, and a mechanism in the storage compartment associated with said exit door and constructed so that it has to be manipulated in a certain manner before the exit door can be moved into its fully open position, even though the entrance door is fully closed.

2. An apparatus for the purpose described, comprising a casing or housing that is adapted to serve as the entrance passageway to a storage compartment, an entrance door and an exit door for said passageway slidingly mounted and arranged so that either of said doors, when in a partially open condition, is disposed in the path of movement of the other door, thus preventing said other door from being opened, a spring-actuated latch on the exit door, a part that co-operates with said latch to maintain it in an inoperative condition when said exit door is fully closed, and to cause said latch to become operative automatically to maintain said exit door in a partially open condition when an attempt is made to move said door towards its open position, a means associated with said latch that requires manipulation in a certain manner before said latch can be actuated to release said exit door, and a device for holding said latch in an inactive condition after it has been actuated to release said exit door.

3. An apparatus for the purpose described, comprising a casing or housing that is adapted to serve as the entrance passageway to a storage compartment, an entrance door and an exit door for said passageway slidingly mounted and arranged at right angles to each other, thereby causing either of said doors, when in a partially open condition, to block or prevent the opening of the other door, a spring-actuated latch on the exit door, a part that co-operates with said latch to maintain it in an inoperative condition when said exit door is fully closed, and to cause said latch to become operative automatically to maintain said exit door in a partially open condition when an attempt is made to move said doors towards its open position, a means associated with said latch that requires manipulation in a certain manner before said latch can be actuated to release said exit door, and a device for holding said latch in an inactive condition after it has been actuated

to release said exit door, said holding device being rendered inoperative automatically by the movement of said exit door back to its fully closed position.

4. An apparatus for the purpose described, comprising a passageway arranged so as to serve as the entrance to a compartment or space in which valuables are stored, an entrance door and an exit door for said passageway arranged in such relation that either of said doors, when in a partly open condition, blocks the other door and prevents the same from being opened, and a means associated with said exit door that requires manipulation before said exit door can be fully opened and also requires manipulation before said exit door can be restored to its fully closed position.

5. An apparatus for the purpose described, comprising a passageway arranged so as to serve as the entrance to a compartment or space in which valuables are stored, a sliding entrance door for said passageway, and a sliding exit door for said passageway, said doors being arranged in such relation that either of said doors when in other than a fully closed condition acts as an abutment which blocks or prevents the other door from being opened.

6. An apparatus for the purpose described, comprising a passageway arranged so as to serve as the entrance to a compartment or space in which valuables are stored, proportioned so that it is not large enough to hold more than one person, a sliding entrance door and a sliding exit door for said passageway arranged in such relation that either of said doors when in an open or partially open condition serves as an abutment that blocks or prevents the opening of the other door, and a lock that operates automatically to lock said exit door in a partially open condition during the act of opening said exit door.

7. An apparatus for the purpose described, comprising a passageway arranged so as to serve as the entrance to a compartment or space in which valuables are stored, a sliding entrance door for said passageway, a sliding exit door for said passageway, said doors being arranged in such relation that either of said doors when in a partially open condition acts as an abutment that blocks or prevents opening of the other door, and a combination lock combined with the exit door for locking the same in a partially open condition, substantially as described.

ANTHONY J. PICHL.
